UNITED STATES PATENT OFFICE.

EMMA C. PEASE, OF NANTUCKET, MASSACHUSETTS.

DESIGN FOR A BOX.

Application filed February 17, 1921. Serial No. 445,898. Term of patent 14 years.

To all whom it may concern:

Be it known that I, EMMA C. PEASE, citizen of the United States, residing at Nantucket, in the county of Nantucket and Commonwealth of Massachusetts, have invented a new, original, and ornamental Design for Boxes Such as are Ordinarily Used for the Holding of Candy or Other Commodities When Sold at Retail, of which the following is a specification, reference being had to the accompanying drawing, which forms a part thereof.

My improved box is substantially oval, in general shape with smooth contour, has certain portions of its exterior surfaces covered with mother-of-pearl, and is provided with a decorated transverse band near one end thereof.

I claim—

The ornamental design for a box, as shown.

In testimony whereof I affix my signature in the presence of two witnesses.

EMMA C. PEASE.

Witnesses:

LAURISTON BUNKER,
EMMA COOK.
